INVENTOR

Joseph P. Centner,

By J. C. Bruch,
Attorney

UNITED STATES PATENT OFFICE.

JOSEPH P. CENTNER, OF PITTSBURG, PENNSYLVANIA.

CAR-BRAKE.

SPECIFICATION forming part of Letters Patent No. 296,274, dated April 1, 1884.

Application filed August 24, 1883. (No model.)

To all whom it may concern:

Be it known that I, JOSEPH P. CENTNER, a citizen of the United States, residing at Pittsburgh, in the county of Allegheny and State of Pennsylvania, have invented certain new and useful Improvements in Railroad-Car Brakes; and I do hereby declare the following to be a full, clear, and exact description of the invention, such as will enable others skilled in the art to which it appertains to make and use the same.

My invention relates to improvements in railway-car brakes; and the object is to produce a railway-car brake that is reliable at all times, automatic in its operation, simple in construction, very powerful in its application, and not liable to get out of order.

The invention consists in the construction and arrangement of certain parts of a railway-car brake, which will be more fully described hereinafter, reference being had to the accompanying drawings, and the letters of reference marked thereon.

Like letters of reference indicate like parts in the different figures of the drawings, in which—

Figure 1 represents a plan view of my improved railway-car brake. Fig. 2 is a longitudinal section of the same. Fig. 3 is a detail view of the draw-bar.

In the drawings, A represents the frame or body of a car of any ordinary construction, having at each end the bumper B. To the inner end of said bumpers are attached the main draw-bars C, connected at the central part of the frame to levers D by means of sliding rods d d. A cross-piece, a, is secured at each end of the frame, between which and the end of the bumper is arranged a spring, e, on the bars C, while another spring, f, is placed between the frame-piece A' and a bar, g, secured to the inner end of the bar C. The rods d slide freely through these bars g with one end, while the opposite ends of said bars are secured to an angle-piece, g', secured to the bars g.

Between the levers D is arranged a pivoted lever, E, which is connected at opposite ends to the outer ends of the levers D by means of the links h, while the extreme ends of said levers D are guided in slotted ways i, secured

to the frame-pieces A''. The central lever is pivoted at k, and is guided on each side in slotted ways l. Toward the ends of the levers are attached the rods m, which pass through angle-pieces n, secured to the central parts, A'', 55 of the frame A, and between the piece A' and the angle-piece n is placed a spring, o, over the rods m. These springs serve to draw the levers D always back to their normal position.

To the extreme outer ends of the central lever, E, are attached the chains or rods p, which connect with the brake-blocks or brake-bars. Another rod, p', extends to and is connected with the ordinary hand brake-shaft q, for operating the brakes by hand. 60

The brakes may be operated by a steam or compressed-air cylinder placed on the locomotive or tender, so as to be operated by the engineer from his cab, or can be manipulated by the ordinary hand brake-wheel on each car. 70 The springs on the bars C also tend to force the levers back to their normal position, and take the brake-blocks out of contact with the wheels, and thus render the brake automatic.

The rods d serve to steady the action of the 75 levers D, and preferably one is placed above and the other below the central lever, E.

It will be readily seen that by this arrangement a very powerful, simple, and reliable brake is obtained, which is not liable to get 80 out of order, and can be easily applied to cars now in use, and is automatic in its operation.

Having thus described my invention, what I claim, and desire to secure by Letters Patent, is—

1. In railway-car brakes, the combination of the draw-bars C, provided with springs e and f, with a central lever, E, connected by links h to the levers D, having attached to them the rods d d, arranged substantially as specified. 90

2. The combination of the draw-bars C, provided with springs e and f, with a central lever, E, connected by links h to the levers D, having attached to them the rods d d and spring- 95 rods m, arranged as shown, and for the purpose set forth.

3. The combination of the draw-bar C, provided with springs e and f, a central lever, E, connected by links h to the levers D, having 100

attached to them the rods *d d* and spring-rods *m*, with the rods and chains *p* and *p'*, for operating the brakes by steam or hand power, substantially as shown and herein specified.

5 4. The brake herein described, consisting of the bumpers *B*, draw-bars *E*, with springs *e* and *f*, the central lever, *E*, side levers, *D*, links *h*, rods *d d*, spring-rods *m*, rods and chains *p p'*, springs *o*, angle-pieces *n*, and suitable

frame, all constructed and arranged substantially as described and shown.

In testimony whereof I hereby affix my signature in presence of two witnesses.

JOSEPH P. CENTNER.
